UNITED STATES PATENT OFFICE

HENRY P. EASTON, JR., OF NUTLEY, NEW JERSEY

GARMENT AND FUR STEAMER

Application filed July 9, 1929. Serial No. 377,018.

This invention relates to steaming devices and pertains particularly to a device for steaming clothes and furs.

The primary object of this invention is to provide a portable device which may have a steam line attached thereto and may be employed for steaming clothes or furs, the clothes being steamed preparatory to pressing, the furs being steamed for the purpose of raising the hairs and generally improving the appearance thereof.

The invention broadly contemplates the provision of an elongated casing having a rounded tube, a portion of which is perforated, the casing being removably positioned over a tray or pan to which is attached a faucet. One end of the casing has a pipe nipple opening therethrough to facilitate the attachment thereto of a steam pipe having connection with a suitable steam generating plant.

The invention will be best understood from a consideration of the following detailed description taken in connection with the accompanying drawing forming a part of the present invention, with the understanding, however, that the invention is not confined to any strict conformity with the showing of the drawing but may be changed or modified so long as such changes or modifications mark no material departure from the salient features of the invention, as expressed in the appended claims.

In the drawing:—

Figure 1 is a view in side elevation of the steamer embodying the present invention.

Figure 2 is a bottom plan view.

Figure 3 is a view in transverse section taken upon the line 3—3 of Figure 1.

Referring to the drawing in detail, the numeral 1 indicates generally the bottom of the present steaming device which bottom, as shown, consists of a tray having the upstanding walls 2 which are inset slightly from the edges of the bottom forming the surrounding flange 3.

Overlying the tray is an elongated hood 4, the bottom of which is open to receive the walls 2, the edges of the hood resting upon the flange 3 outside of the tray walls.

The top of the hood 4 is rounded or of substantially parabolic cross sectional design, as shown in Figure 3, and the major portion of the hood wall from one end is provided with relatively closely spaced apertures 5, a section of the hood adjacent the other end being left imperforate, as shown. Formed integrally with the top-most portion of the imperforate section of the hood and opening therethrough is a pipe nipple or coupling 6 to which is swivelly connected, as at 7, one end of a flexible tube 8 carrying a second swivel connection 9 upon its other end to facilitate the attachment thereto of a suitable steam pipe (not shown).

Each end of the hood 4 is closed by an end wall 10 and extending through one end wall and through the adjacent end wall of the tray is a draw-off faucet 11 which may be employed for removing condensed steam from the tray.

At each longitudinal side of the tray there are secured loops or eyes 12, each of which has attached thereto a spring 13, which, when the steaming device is placed upon a support, such for example as a bench or ironing table, may be passed beneath the support and connected together in any suitable manner, as for example by hook members such as those shown.

It will, of course, be readily understood that this steaming device, in addition to being secured to a flat supporting surface, such as a table or the like, may be hung up by engaging those eyes to which are attached the springs 13 over suitable supporting hooks.

From the foregoing description it will be readily seen that with a device of the character herein described articles of clothing, furs, etc., may be readily steamed and the device may be conveniently transferred from place to place. The steaming operation is carried out by placing the garment over the body or hood 4 and steam is admitted thereto and allowed to rapidly escape from the apertures 5 to pass through the garment. This rapid passage of steam through the garment blows the dust therefrom and at the same time kills any germs which might be in the fabric of the garment.

Having thus described my invention, what I claim is:—

1. A steaming device of the character described comprising an elongated casing of substantially parabolic cross sectional design having an open bottom, a tray having up-standing walls inset from the edges of the bottom thereof, said walls being adapted to extend into the casing, means for introducing steam into the casing, and means for drawing-off condensed steam from the tray, said casing wall from one end throughout the major portion thereof having steam outlet apertures, said steam introducing means being adjacent the other end.
2. A steaming device of the character described comprising an elongated casing of substantially parabolic cross sectional design having an open bottom, a tray having up-standing walls inset from the edges of the bottom thereof, said walls being adapted to extend into the casing, means for introducing steam into the casing, means for drawing-off condensed steam from the tray, said casing wall from one end throughout the major portion thereof having steam outlet apertures, said steam introducing means being adjacent the other end, and means for suspending said steaming device from supporting elements.
3. In a steaming device of the character described including a base, means for securing said base to a supporting table structure, comprising eye members secured to opposite side edges of the base, and spring members secured at one end to certain of said eyes and adapted to be passed beneath the supporting structure and connected at their other ends to adjacent eyes.
4. In a steaming device of the character described including a base, means for securing said base to a supporting table, comprising eye members secured to opposite edges of the base, a spring attached at one end to each of said eyes, and means carried by the other ends of the springs for connecting the same together beneath the supporting table.
5. A steaming device, comprising an elongated casing having a rounded top surface and an open bottom, a detachable tray like bottom normally closing the open bottom of the casing, means for introducing steam into the casing, and means for drawing off condensed steam from said tray like bottom, said casing having the major portion of the rounded top surface from one end provided with steam outlet apertures, and means for introducing steam into the casing adjacent the other end thereof.

In testimony whereof I hereunto affix my signature.

HENRY P. EASTON, JR.
